DESIGN FOR A BRACKET.

JOHN H. BELLAMY, OF CHARLESTOWN, MASSACHUSETTS.

Design No. 2,524, dated December 11, 1866.

The Schedule referred to in these Letters Patent and making part of the same.

TO WHOM IT MAY CONCERN:

Be it known that I, JOHN H. BELLAMY, of Charlestown, in the county of Middlesex, and State of Massachusetts, have invented a new and improved Design for a Bracket; and I hereby declare that the following is a full and exact description thereof, reference being had to the accompanying photograph drawing, and to the letters of reference marked thereon.

My invention consists of a design for a bracket, embracing certain emblematic symbols, which constitute principally the body and outline of it, and which are arranged relatively in the construction of it as follows, to wit:

Above the shelf, (A,) is an arch, (1,) on which are inscribed the letters I N R I, (2); beneath the arch is a cross, (3,) on which is a crown of thorns, (4,) encircling the upper limb of it; three nails, (5,) a hammer, (6,) a pair of pincers, (7,) a spear, (8,) a sponge upon a staff, (9,) and a ladder, (10.) Below the shelf, (A,) is a pillar, (11,) with a rope attached, (12,) and on either side of the pillar a bunch of lashes attached to a staff, (13;) the shelf being supported by ornamental scroll work, (14,) the whole forming an open-work design.

What I claim as my invention, and desire to secure by Letters Patent, is—

The design for a bracket, substantially as shown and described.

JOHN H. BELLAMY.
